(57) **CLAIM**

The ornamental design for an underwater propeller, as shown and described.

DESCRIPTION

FIG. 1 is a front, left side perspective view of an underwater propeller showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, left side perspective view thereof in a second configuration;

FIG. 9 is a front perspective view a thereof in a third configuration;

FIG. 10 is a front, right side perspective view thereof in a fourth configuration;

FIG. 11 is a rear, right side perspective view thereof in a second configuration; and,

FIG. 12 is an enlarged view of portion 12 shown in FIG. 6. The portions of the article shown in broken line form no part of the claimed design. The additional broken lines in the FIGS. 6 and 12 illustrate the boundaries of the enlarged view indicators and form no part of the claimed design.
